(57) CLAIM

The ornamental design for a binder, as shown and described.

DESCRIPTION

FIG. 1 is a front perspective view of a binder, showing my new design in a closed state;

FIG. 2 is rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of portion 9 shown in FIG. 1;

FIG. 10 is a partial enlarged view of portion 10 shown in FIG. 2;

FIG. 11 is a partial enlarged view of portion 11 shown in FIG. 3;

FIG. 12 is a partial enlarged view of portion 12 shown in FIG. 5;

FIG. 13 is a partial enlarged view of portion 13 shown in FIG. 6;

FIG. 14 is a partial enlarged view of portion 14 shown in FIG. 7;

FIG. 15 is a partial enlarged view of portion 15 shown in FIG. 8;

FIG. 16 is a perspective view of the binder in an open state; and,

FIG. 17 is a partial enlarged view of portion 17 shown in FIG. 16.

The short evenly spaced broken lines in the figures depict environment and form no part of the claimed design. In addition, the long evenly spaced broken lines indicating the enlargement portions of the design form no part of the claimed design.

1 Claim, 15 Drawing Sheets
